UNITED STATES PATENT OFFICE

167,455

RETINAL CAMERA

Robert V. Gerhardt, Rochester, N. Y., assignor
to Bausch & Lomb Optical Company, Rochester,
N. Y., a corporation of New York

Application September 29, 1951, Serial No. 16,789

Term of patent 14 years

(Cl. D61—1)

To all whom it may concern:

Be it known that I, Robert V. Gerhardt, a citizen of the United States and a resident of Rochester, county of Monroe, and State of New York, have invented a new, original, and ornamental Design for a Retinal Camera, of which the following is a specification, reference being had to the accompanying drawing, forming a part hereof.

Fig. 1 is a front perspective view of a retinal camera, showing my new design.

Fig. 2 is a rear perspective view of the same.

I claim:

The ornamental design for a retinal camera, substantially as shown.

ROBERT V. GERHARDT.
